UNITED STATES PATENT OFFICE.

JEAN BAPTISTE SABOURIN, OF NORTON, MASSACHUSETTS, ASSIGNOR TO EISENSTADT MANUFACTURING COMPANY, OF ST. LOUIS, MISSOURI, A CORPORATION OF MISSOURI.

CUFF-BUTTON.

1,382,123.

Specification of Letters Patent. Patented June 21, 1921.

Application filed March 30, 1921. Serial No. 456,879.

To all whom it may concern:

Be it known that I, JEAN BAPTISTE SABOURIN, a citizen of the United States of America, residing at the town of Norton, 5 county of Bristol, State of Massachusetts, United States of America, have invented a certain new and useful Cuff-Button, of which the following is such a full, clear, and exact description as will enable any one 10 skilled in the art to which it appertains to make and use the same, reference being had to the accompanying drawings, forming part of this specification.

My invention relates to a cuff button of 15 the type illustrated in Jacobs United States Patent No. 1,341,130 having two separable parts and more particularly to improved means for locking the parts together and releasing them. The object of the invention 20 is to provide a reliable locking device which can be positively and easily released. While I have shown the invention embodied in a cuff button it can, of course, be embodied in other kinds of garment fasteners.

25 In the accompanying drawings, Figure 1 is a view partly in elevation and partly in central longitudinal section of a cuff button embodying my invention and showing the parts in locked position. Fig. 2 is a sectional view on line 2—2 of Fig. 1 and Fig. 3 is a 30 view similar to Fig. 1 showing the parts applied to the cuff and the locking parts in released position.

1 is a barrel to which is attached the cuff 35 engaging member comprising, in the form shown, two disks 2 and 3. The locking members 4 have inturned flanges at their outer ends and are engaged at the other ends by a disk 5 movable in the barrel and impelled by the spring 6. A flanged sleeve 7 is slidably supported in the barrel and carries cuff engaging disk 8. The flange on the sleeve engages with an interior shoulder on the barrel at one side and the other side is 40 tapered and engages with the outer ends of the locking members 4. The other part of the button comprises cuff engaging disks 9 and 10 and a locking post 11 with an enlarged head or flange 12 which in the locking 45 position of the parts is engaged by the inturned flanges on the locking members 4.

The two parts of the button are brought 50 into locking relation by inserting the post 11 in the sleeve 7, the flanged end of the post 55 engaging the inwardly tapered surfaces of

the locking members and forcing them downward and then apart sufficiently to allow the movement of the post to its locking position when the upper ends of the locking members are brought into that portion of 60 the barrel which is of larger internal diameter than the portion occupied in the locking position. After the end of the post has passed the locking flanges on the members 4, the spring will cause these members to return to the position shown in Fig. 1 and engage the shoulder on the post and securely hold it from withdrawal. To release the lock, the sleeve 7 is impelled inward by 65 finger pressure on the disk 8 which operation 70 first moves all of the parts relatively to the barrel and when the upper ends of the locking members have been passed to alinement with the enlarged portion of the barrel they are impelled outward by the tapered surface 75 of the end of the sleeve toward position shown in Fig. 3 and out of engagement with the locking post thereby permitting the withdrawal of the post from the sleeve.

Having fully described my invention what 80 I claim as new and desire to secure by Letters Patent of the United States is:

1. A button comprising two separable parts each adapted to engage with a button hole in a garment, one of said parts being 85 provided with a locking post and the other with a locking member engaging with the post, means tending to hold said member in locking position and a manually operated member adapted to move said locking member to release position.

2. A button comprising two separable parts each adapted to engage with a button hole in a garment, one of said parts being provided with a locking post and the other 95 with a locking member engaging with the post, resilient means tending to hold said member in locking position and a slid able member adapted to move said locking member to release position.

3. A button having two separable parts, one of said parts comprising a barrel carrying a garment engaging member and a sleeve movable in said barrel and also carrying a garment engaging member, a locking post carried by the other part of the button and insertible in the first mentioned part through the sleeve, and locking members in the barrel adapted to engage with the post, said sleeve being adapted to engage with the 110

locking members to force them to release position.

4. A button having two separable parts, one part carrying a locking post, and the other part comprising a barrel, a spring impelled disk therein, locking members in the barrel and engaged by the disk to hold them in locking position relative to the post, and

a sleeve slidable in the barrel and through which the locking post extends, the extremity of said sleeve having a tapered surface to engage with the locking members to force them to release position. 10

In testimony whereof I have hereunto set my hand and affixed my seal.

JEAN BAPTISTE SABOURIN. [L. S.]
